RELAY

Wheeler D. Maynard, Mendon, N.Y., assignor to General
Railway Signal Company, Rochester, N.Y.

Filed Nov. 9, 1962, Ser. No. 72,442

Term of patent 14 years

(Cl. D26—13)

FIG. 1

FIG. 2

FIG. 3

FIG. 1 is a view in perspective of a relay showing my new design;

FIG. 2 is a bottom view thereof; and
FIG. 3 is a reverse side elevation.

I claim:

The ornamental design for a relay, as shown.
